BED FOR SMALL ANIMALS AND THE LIKE

Leland W. Bell, 421 Hawthorne St., Glendale, Calif.

Filed Mar. 8, 1965, Ser. No. 84,150

Term of patent 3½ years

(Cl. D12—2)

FIG. 1 is a perspective view of a bed for small animals and the like, showing my new design,

FIG. 2 is a side elevational view in reduced scale as viewed from the right hand side of FIG. 1 and showing the top component separated from the base component,

FIGS. 3, 4, 5 and 6 are, respectively, top plan, front elevational, rear elevational and bottom plan views, and

FIGS. 7 and 8 are enlarged, fragmentary, sectional views taken, respectively, on the lines 7—7 and 8—8 of FIG. 1.

I claim:

The ornamental design for a bed for small animals and the like, substantially as shown and described.
